UNITED STATES PATENT OFFICE.

JACOB LOWE YOUNG, OF NEW ROCHELLE, NEW YORK.

DENTAL APPLIANCE.

1,378,306.

Specification of Letters Patent. Patented May 17, 1921.

Application filed July 13, 1920. Serial No. 395,835.

To all whom it may concern:

Be it known that I, JACOB LOWE YOUNG, a citizen of the United States, and resident of New Rochelle, in the county of Westchester and State of New York, have invented certain new and useful Improvements in Dental Appliances, of which the following is a specification.

This invention relates to improvements 10 in dental appliances for use in shaping a strip of band-forming metal about a tooth, or for contracting a loop of flexible material about a tooth to measure the tooth for a band.

15 The invention has for its general object to provide a simple and efficient appliance of the class above set forth which may be readily adapted for use in contracting a loop of material about any tooth in either 20 the upper or lower dental arch without difficulty and with little or no discomfort to the person whose teeth are to be fitted with bands.

Another object of the invention is to 25 provide an appliance of the class set forth which may be conveniently held and manipulated with one hand in placing the looped strip of material about a tooth and contracting the loop.

30 The improved appliance embodies a pair of pivoted members forming a loop-holding pliers and a reversible third lever member for contracting the loop of material about a tooth, and further objects of the invention 35 are to provide means for pivotally connecting the third lever member to the pliers so that the handle portion thereof will swing in the same plane as the handles of the pliers, to provide means for pivotally connecting the third lever member with the 40 pivot pin of the members of the pliers, and to provide simple means for locking the third member on either side of the pliers to prevent accidental disconnection of the 45 pliers and loop-contracting member while permitting free pivotal movement of said member about the pivot pin of the pliers.

In the drawings:

Figure 1 is a plan view of the appliance 50 holding a looped strip of band-forming metal in position for use;

Fig. 2 is an enlarged fragmentary side elevation of the appliance;

Fig. 3 is a plan view of the detachable and 55 reversible loop-contracting member;

Fig. 4 is a side elevation of the loop-con-

tracting member, showing the inner side thereof;

Fig. 5 a detail sectional view on the line 60 V—V of Fig. 4;

Fig. 6 a detail sectional view on the line 65 VI—VI of Fig. 2;

Fig. 7 an enlarged transverse section on the line VII—VII of Fig. 1; and

Fig. 8 a fragmentary plan view of a 70 modified form of separably interlocked pivotal connection between the loop-holding and loop-contracting members.

Referring to the drawings by numerals, 75 1 and 2 designate the crossed pivotally connected lever members of the loop-holding means or pliers and 3 designates the third lever member or reversible loop-contracting device. The member 1 is provided with the centrally slotted flattened intermediate portion 1^a through which the reduced flat portion 2^a of member 2 extends, as is usual in crossed-handle dental pliers. The crossed members are pivotally connected at their point of intersection by a pivot pin 4 which 80 extends loosely through an aperture in flat portion 2^a of member 2 and is tightly held by a driving fit in apertures in the slotted flat portion 1^a of member 1, as shown more clearly in Fig. 7. By this construction the 85 pin 4 is fixed in member 1 against rotary and endwise movement while member 2 is free to swing about the pin as a pivot.

The pin 4 has reduced cylindrical end 90 portions which project beyond the outer side faces of the part 1^a of member 1 and the loop-contracting member 3 is provided intermediate its ends at opposite sides thereof with a pair of ears or lugs 5 adapted to embrace the flattened portion 1^a of member 1, said pivot lugs or ears being slotted at 6 to receive the reduced end portions of the pivot pin 4. The handle portion of member 3 is preferably of rounded channel 95 form as shown and is adapted to partly embrace the handle portion of member 1 or 2 when pressed toward the same to permit a maximum pivotal movement of the member 3.

The gripping ends of members 1 and 2 100 are provided with jaws 11 and 12 respectively extending laterally, and preferably slightly forwardly, the gripping faces of which when in engagement lie in a plane parallel with the pivotal axis of the members 1 and 2. The jaw 11 is provided with a longitudinal rib 13 and jaw 12 with a 110

complementary groove or channel 14 in order that the ends of a doubled strip of material may be tightly gripped between the jaws with the looped strip extending 5 longitudinally of the appliance. The member 3 at the opposite side of its pivot from the handle portion thereof is provided with a relatively flat portion 7 provided with two arms or projections 8 extending laterally 10 and forwardly from the side edges of the forward end thereof at the same angle so that one or the other of these arms 8 will lie alongside the jaws 11 and 12 when the reversible member 3 is connected with the 15 pliers at either side thereof. The arms 8 are provided with slots 9 extending inwardly from the outer ends of the arms, preferably in alinement with the forward side edges of the plier jaws, as shown, and 20 the walls of these slots are preferably beveled adjacent the outer ends of the arms at the inner faces of the arms to facilitate the entrance of the doubled strip of band material into the slots.

25 In Figs. 1 to 7 I have shown one means for detachably locking the member 3 on the pliers to swing about pivot pin 4, which means comprises a U-shaped locking slide 15 provided with slots 16 extending transversely of the slots 6 in ears 5 of member 3 and adapted to receive the reduced outer ends of the pivot pin 4, as shown in Fig. 1, when the slide is moved forwardly on member 3 from the position shown in Figs. 3 to 30 5. The slide 15 is held to member 3 by a headed stud or the like 17 the reduced shank of which extends through a slot 18 in member 3. In Fig. 8 a modified form of separably interlocked pivotal connection is shown. 35 40 In this construction the pivot ears 5 of member 3 are provided with inclined slots 19 to receive the ends of pivot pin 4 and the rear edges of the lugs are curved on an arc about the center of pin 4 to form hook-like lock 45 lugs 5^a the rear arcuate edges of which engage pins or projections 20 on opposite sides of part 1^a when the member 3 is in place to prevent rearward movement of said member while the forward edges of said lugs 50 prevent forward and lateral movement of the member. It will be seen, therefore, that member 3 can be connected with either side of the pliers by passing lugs 5^a simultaneously inwardly and forwardly between pin 4 and projections 20 and may be disconnected only by an outward and rearward pull. In both constructions member 3 is provided with a flat spring 10 the free end of which loosely engages the handle portion of either 55 60 member 1 or 2, according to the side of the pliers upon which member 3 is mounted, and normally presses one of the arms 8 against the adjacent jaw of the pliers.

The operation is as follows:

65 A thin strip of band-forming metal, or

other flexible material, is doubled to form a loop and the ends of the doubled strip are then passed between the jaws 11 and 12 with the loop at the forward side of the jaws. The handles of the pliers are then pressed toward each other to cause the jaws 11 and 12 to tightly grip the doubled strip and then locked by swinging a bail 21 pivoted to handle 2 over the notched end of handle 1 of the pliers. The member 3, detached from the pliers is then placed substantially at right angles to the pliers, at the proper side of the pliers according to the location of the tooth, and the looped strip is passed into the slot 9 of the arm 8 which extends parallel with the plier jaws. The handle end of member 3 is then connected with pivot pin 4 in either of the two ways above described, or otherwise pivotally connected with the pliers to swing in a plane parallel with the plane of the pliers. The complete appliance is then held in one hand while the other hand is used to assist in passing the loop about a tooth. It will be obvious that by contracting the fingers of the hand holding the appliance to press the handle end of member 3 inwardly against the tension of spring 10 the band 22 may be tightly contracted on the tooth.

90 The outer sides of the arms 8 which press against the teeth may be shaped to conform to the contour of the tooth, and a series of members 3 may be provided each having the outer sides of its arms 8 of proper contour for use with teeth of a particular class.

95 What I claim is:

1. A dental appliance comprising three lever members pivotally connected to swing about a common axis, each of two of said members having a gripping jaw at one end thereof and the other member being provided with a slot open at one end, said slot being located adjacent the jaws on the other members when the three adjacent ends of the members are in close juxtaposition. 105 110

2. A dental appliance comprising three lever members pivotally connected to swing about a common axis, each of two of said members being provided with a gripping jaw and the third member being provided 115 with a restricted opening adjacent the jaws on the other members, and means for locking the two jaw-carrying members against pivotal movement relatively to each other with the jaws in clamping relation. 120

3. A dental appliance comprising three lever members pivotally connected to swing about a common axis, each of two of said members being provided with a gripping jaw and the third member being provided 125 with a restricted opening adjacent the jaws on the other members, means for locking the two jaw-carrying members against pivotal movement relatively to each other with the jaws in clamping relation, and 130

- resilient means normally forcing the apertured portion of the third member toward the jaw-carrying ends of the other members.
- 5 4. A dental appliance comprising a pair of plier members having jaws at one end and handle portions, a loop-contracting member having a slot adjacent one end and a handle portion, means connecting the 60
10 three members to swing relatively to each other about a common axis, means for locking the handle portions of the plier members against relative movement, and resilient means for normally forcing the handle 65
15 portion of the loop-contracting member away from the locked handle portions of the pliers.
5. A dental appliance comprising a pair of pliers having members pivotally connected together intermediate their ends and each provided with a handle portion at one side of its pivot and a gripping jaw at the other side of its pivot, and a loop-contracting member pivotally supported on the 70
20 pliers to swing about an axis extending transversely of the plane of movement of the members of the pliers, said member having a handle portion at one side of its pivot adjacent the handle portion of one member 75
25 of the pliers and a restricted opening at the other side of its pivot.
6. A dental appliance comprising a pair of pliers having lever members provided with gripping jaws at one end, a reversible 80
30 loop-contracting lever member provided with an opening adjacent one end, and means for detachably and pivotally connecting said loop-contracting member with the pliers intermediate its ends to swing about 85
35 an axis extending transversely of the plane 90
40 of pivotal movement of the lever members of the pliers with the apertured end of the loop-contracting member located at one side or the other of the gripping jaws.
- 45 7. The combination of a pair of lever members having gripping jaws, a pivot pin connecting the lever members having projecting end portions, and a third lever member having parallel ears fulcrumed on the 95
50 projecting end portions of said pivot pin and provided with a restricted opening at one side of its pivot adjacent the jaws on the other members.
8. A dental appliance comprising a pair 100
55 of pliers the members of which are provided with laterally offset jaws having gripping faces extending longitudinally of the pivotal axis of the members, a reversible loop-contracting member having two restricted 105
60 openings therethrough each of which is so located as to lie adjacent the jaws of the pliers in one position of the reversible loop-contracting member, and means for pivotally and detachably connecting the loop-contracting member with the pliers to swing in a plane parallel with the members of the pliers with said loop-contracting member extending longitudinally of the pliers alongside either edge of the pliers.
9. A dental appliance comprising a pair 70
75 of pliers the members of which are provided with laterally offset jaws having gripping faces extending longitudinally of the pivotal axis of the members, a reversible loop-contracting member adapted to be connected with the pliers alongside either edge of the pliers and having two restricted openings therethrough each of which is so located as to lie adjacent the jaws of the pliers in one position of the reversible loop-contracting member, means for pivotally and detachably connecting the loop-contracting member with the pliers to swing in a plane parallel with the members of the pliers, and a spring held to the loop-contracting member and adapted to loosely engage one of the plier members in either position of the loop-contracting member.
10. A dental appliance comprising a pair 80
85 of lever members provided with laterally offset jaws at one end, a pivot pin connecting said members intermediate their ends and having projecting end portions, a third lever member having two slotted arms extending from opposite sides thereof adjacent one end, and a pair of pivot ears on said third member adapted to embrace the other two members and having open slots to receive the projecting ends of the pivot pin.
11. A dental appliance comprising a pair 90
95 of lever members provided with laterally offset jaws at one end, a pivot pin connecting said members intermediate their ends and having projecting end portions, a third lever member having two slotted arms extending from opposite sides thereof adjacent one end, a pair of pivot ears on said third member adapted to embrace the other two members and having open slots to receive the projecting ends of the pivot pin, 100
105 and a U-shaped slide shiftable longitudinally on said third member embracing said pivot ears and provided with open slots for receiving the ends of the pivot pin extending transversely of the slots in said ears.
- In testimony whereof I hereunto affix my signature.

JACOB LOWE YOUNG.
